Primary Examiner — Mark Goodwin*(74) Attorney, Agent, or Firm* — Saidman Design Law Group(57) **CLAIM**

The ornamental design for a sidebar protector, as shown and described.

DESCRIPTION

FIG. 1 is a front perspective view of a sidebar protector showing our new design;

FIG. 2 is a left side view thereof;

FIG. 3 is a right side view thereof;

FIG. 4 is a rear view thereof;

FIG. 5 is front view thereof;

FIG. 6 is a top view thereof;

FIG. 7 is a bottom view thereof; and,

FIG. 8 is a rear perspective view thereof.

The uniform dashed broken lines illustrate structure or features that form no part of the claimed design.

The dot-dash broken lines illustrate boundaries of the claimed design; the boundaries themselves form no part of the claimed design.

The drawings include surface shading that represents contour and not surface ornamentation.
